Des. 188,291
Patented June 28, 1960

188,291

RACK FOR DISH WASHING MACHINES

Manny L. Weiss, 69—53 179th St., Flushing, N.Y.

Filed July 7, 1959, Ser. No. 56,692

Term of patent 14 years

(Cl. D49—1)

Fig. 3.

Fig. 4.

Fig. 5.

Fig. 1 is a top plan view of a rack for dish washing machine, showing my new design;

Fig. 2 is a bottom plan view thereof;

Fig. 3 is a front elevational view thereof;

Fig. 4 is a vertical sectional view taken on the line 4-4 of Fig. 1; and

Fig. 5 is a perspective view thereof.

I claim:

The ornamental design for a rack for dish washing machines, substantially as shown.
